UNITED STATES PATENT OFFICE

2,537,860

SLIDABLE JAW WRENCH

Ralph W. Root, Chicago, Ill.

Application March 24, 1948, Serial No. 16,709

2 Claims. (Cl. 81—179)

1

This invention relates to a wrench. More particularly, this invention relates to a wrench which is particularly adapted for use on nuts and bolt heads in places in which it is difficult to raise or remove and retract the wrench after each operative movement or advancing stroke thereof upon such a nut or bolt head. Thus the present wrench is designed and constructed so that it may be retracted after each operative movement or stroke thereof without raising or lowering it upon or removing it from the nut or bolt head after each operative movement or advancing stroke thereof.

I am aware that heretofore wrenches have been made which have included a handle, a head, a stationary jaw on the head, and a jaw which is movable relative to and upon the head of the wrench, against the action of a spring, so as to facilitate use and operation of the wrench in places in which it is difficult to raise and retract the wrench after each operative movement or advancing stroke thereof upon a nut or bolt head.

However, insofar as I am aware, none of such prior wrenches has made provision for enabling either one of the two jaws of the wrench to be rendered selectively movable upon and relative to the head of the wrench while, at the same time, latching the other jaw against movement relative to and upon the head of the wrench in the use thereof.

Accordingly, an object of the present invention is to provide a new and improved wrench including a handle portion, a head, a pair of jaws movably mounted on the head of the wrench, and manually adjustable means mounted on and carried by the head of the wrench while, at the same time, allowing the other jaw to move relative to and upon the head of the wrench during the operation of turning a nut or bolt head.

Another object of the present invention is to provide in the new wrench a novel device for selectively latching either of the jaws relative to and upon the head of the new wrench and against movement relative thereto.

An additional object of the invention is to provide in the new wrench a novel construction and arrangement for varying or adjusting the effective width of the space between the jaws on the new wrench so as to enable the new wrench to be adjusted or accommodated to nuts and bolt heads of slightly varying or different sizes.

Other and further objects of the present invention will be apparent from the following description and claims and are illustrated in the

2

accompanying drawing which, by way of illustration, shows preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

Fig. 1 is a top plan view of a wrench embodying my invention;

Fig. 2 is a front end elevational view as seen from the top in Fig. 1;

Fig. 3 is a fragmentary plan sectional view illustrating the construction of the new wrench;

Fig. 4 is a transverse sectional view on line 4—4 in Fig. 3;

Fig. 5 is a fragmentary detail sectional view on line 5—5 in Fig. 1 illustrating the construction of the adjustable gripping plate embodied in the new wrench, together with the novel means for adjusting the same upon and relative to the jaw on which the said gripping plate is mounted;

Fig. 6 is a fragmentary sectional view on line 6—6 in Fig. 1;

Fig. 7 is a perspective view illustrating the construction of one of the movable jaws embodied in the new wrench; and

Fig. 8 is a fragmentary plan view illustrating the construction of the head of the new wrench with the cover plate therefor removed.

A preferred embodiment of the new wrench is illustrated in the drawing, wherein it is generally indicated at 10, and comprises a handle 11 and a head portion 12 formed integrally therewith.

The head portion 12 of the new wrench 10 has a pair of diverging slots or sockets 13 and 14 formed therein and these slots or sockets 13 and 14 are interconnected by a curved or arcuate slot or recess 15 which is also formed in the head portion 12 of the wrench 10. Thus, as shown in Fig. 8, the slots or sockets 13 and 14 and the slot 15 form a continuous slot or recess in the head 12 of the new wrench.

As shown in the drawing, the new wrench 10 includes a movable clamping jaw 16 and a movable clamping jaw 17. The movable clamping jaw 16 includes a tongue or base portion 18, which is slidably mounted in the slot or socket 13 in the head 12 of the wrench, and the movable jaw 16 also includes a head or gripping portion 19. Similarly, the movable jaw 17 includes a tongue

or base portion 20, which is slidably mounted in the slot or socket 14, and a gripping head 21.

As best shown in Fig. 3, the tongue portions 18 and 20 of the movable jaws 16 and 17 are interconnected by a coil tension spring 22 which is disposed within the arcuate slot or recess 15 which is formed in the head 12. One end portion of this coil tension spring 22 is attached to a pin 23 which is mounted in an opening 46 in the base or tongue portion 18 of the movable jaw 16 (Fig. 3) and the other end portion of the coil tension spring 22 is attached to a similar pin 24 which is mounted in an opening 47 in the tongue portion 20 of the movable jaw 17, (Figs. 3 and 7).

The tongue portion 18 of the movable jaw 16 has a latching notch or recess 25 formed therein upon its inner side surface and the tongue portion 20 of the movable jaw 17 has a similar latching notch or recess 26 formed therein upon its inner said surface. The head 12 of the wrench 10 has a transverse slot 27 formed therein and this transverse slot 27 extends between and interconnects the two slots or sockets 13 and 14, (Fig. 8). A latch member or bar 28 is slidably mounted in the transverse or interconnecting slot 27.

This slidable latch member or bar 28 has an end portion 29 which is latchingly engageable in the latching notch or recess 25 which is formed in the tongue portion 18 of the movable jaw 16 and the slidable latch member or bar 28 has an end portion 30 which is latchingly engageable in the latching notch or recess 26 which is formed in the tongue portion 20 of the movable jaw 17. A knurled finger grip or handle element 31 is mounted on the slidable latch member or bar 28 approximately midway between the ends thereof and this knurled finger grip or handle element 31 works in and projects through an elongated slot 32 which is formed in a cover plate 33 which is attached to the head 12 of the wrench 10 by means of a suitable fastening element in the form of a countersunk screw 34, (Fig. 1). It will be noted, in this connection, that the cover plate 33, when mounted in position of use, lies in the recessed surface of the head 12 formed by the slots or sockets 13 and 14 of the recess 15 and lies flush with the outer surface of the handle 11 (Figs. 2, 4 and 6).

As shown in Fig. 3, the head portion 19 of the movable jaw 16 has an adjustable gripping member or plate 35 mounted thereon on its inner surface. This adjustable gripping member or plate 35 is adjustably and slidably mounted upon the head 19 of the movable jaw 16 by means of a relatively short guide pin 36 and a relatively long guide pin 37 which are integrally attached at their inner ends to the adjustable gripping plate 35. These guide pins 36 and 37 are slidably mounted in and work in holes 38 and 39, respectively, which are formed in the head 19 of the movable jaw 16. The adjustable gripping plate 35 has a screw 40 attached thereto between the guide pins 36 and 37 and this screw 40 is arranged in a slot or opening 41 which is formed in the head 19 of the movable jaw 16. A knurled finger grip member 42 is threaded onto the screw 40 between the ends thereof and this knurled finger grip member 42 works in a slot 43 which is provided therefor in the head 19 of the movable jaw 16 (Figs. 3 and 5). In order to facilitate access to the knurled finger grip member 42 the side portions of the head

19 of the movable jaw 16 are recessed as at 44 and 45 (Fig. 5).

The use and operation of the new wrench are as follows: The parts of the new wrench may be assembled as shown in the drawing. When thus assembled either of the two movable jaws 16 and 17 may be conditioned for sliding movement relative to and upon the head 12 of the wrench by manipulating the knurled finger grip 31 on the slidable latch member 28. Thus, if it is desired to render the jaw 16 movable relative to and upon the head 12 of the wrench this may be accomplished by sliding the slidable latch member 28 to the left, as seen in Fig. 1, so as to project the end portion 30 of the slidable latch member 28 into the latching notch or recess 26 in the tongue or base portion 20 of the movable jaw 17, thereby latching the jaw 17 against slidable movement upon and relative to the head 12 of the wrench. When the new wrench is then applied to a nut or bolt head the jaw corner portion of the nut or bolt head will engage the lower inside corner portion of the gripping plate 35 on the head 19 of the movable jaw 16 and will thereupon slide the movable jaw 16 outwardly in its slot or socket 13 in the head 12 of the wrench 10, thereby enlarging the space between the two jaws 16 and 17 due to the angular relationship of the sockets or slots 13 and 14 in the head 12 of the wrench 10. As the inner surface of the gripping plate 35 on the head 19 of the jaw 16 moves over the surface of the nut or bolt head the coil tension spring 22 will retract the movable jaw 16 in its socket 13.

In this manner the new wrench may be employed to manipulate a nut or bolt head without removing it therefrom.

When it is desired to render the jaw 17 movable upon and relative to the head 12 of the wrench this may be accomplished by manipulating the finger grip member 31 so as to move the latch bar 28 into the position in which it is shown in Figs. 1 and 3, thereby projecting the end portion 29 of the latch bar 28 into latching engagement in and with the latching notch or recess 25 which is formed in the tongue or base portion 18 of the jaw 16. In this manner the jaw 16 is latched against movement upon and relative to the head 12 of the wrench 10 while, at the same time, the jaw 17 is rendered movable relative thereto.

During the use of the wrench, when the parts are thus arranged, the jaw 17 will be urged outwardly in the slot or socket 14, against the action of the coil tension spring 22, by jamming engagement of a corner of the nut or bolt head against the lower inside corner portion 48 of the head portion 21 of the jaw 17 and, thereby will enlarge the space between the heads 19 and 21 of the jaws 16 and 17, respectively, due to the diverging relationship of the slots or sockets 13 and 14 in the head 12 of the wrench 10. As the head portion 21 of the movable jaw 17 passes over the surface of the nut or bolt head, the coil tension spring 22 will retract the movable jaw 17 in its slot or socket 14 in the head 12 of the wrench 10.

The effective width or thickness of the movable jaw 16 may be varied, so as to vary the effective width of the space between the head portions 19 and 21 of the jaws 16 and 17 and thus accommodate the new wrench to nuts and bolt heads of slightly different or varying sizes. This may be accomplished by rotating the knurled

finger grip wheel or disc 42 upon the screw 40 and within the slot or recess 43 in which the wheel or disc 42 is mounted (Figs. 3 and 5). This operation enables the gripping plate 35 to be moved inwardly or outwardly relative to the body portion of the head 19 of the jaw 16 so as to vary the effective width of the space between the heads 19 and 21 of the jaws 16 and 17 and thus adjust the effective size of the wrench to nuts or bolt heads of slightly varying sizes. During this operation the plate 35 is guided by movement of the guide pins 36 and 37 in the holes 38 and 39. When it is desired to retract the gripping plate 35 into the position in which it is shown in Figs. 1 and 2 of the drawing this may be accomplished by rotating the disc or wheel 42 in a direction opposite to the direction in which the disc or wheel 42 is rotated to move the gripping plate 35 outwardly relative to the main body portion of the head 19 of the clamping jaw 16.

It will be noted that the single coil tension spring 22 retains the movable jaws 16 and 17 in the guide slots 13 and 14 provided therefor in the head 12 of the wrench while permitting selective slidable movement of the two jaws in the slots 13 and 14, as explained hereinbefore.

It will thus be seen from the foregoing description, considered in conjunction with the accompanying drawing, that the present invention has the desirable advantages and characteristics, and accomplishes its intended objects, including these hereinbefore pointed out and others which are inherent in the invention.

I claim:

1. A wrench comprising a handle and a head formed integrally therewith, the said head of the wrench having a pair of diverging sockets formed therein, a gripping jaw slidably mounted in each of the said sockets, a coil tension spring mounted in the said head of the wrench between the said gripping jaws and their sockets and having its end portions attached to the said gripping jaws, the said coil tension spring being adapted to be expanded by outward sliding movement of the said gripping jaws upon and relative to the said head of the wrench and to retract the said gripping jaws into their aforesaid sockets after each outward movement thereof, and manually ad-

justable means slidably mounted in the said head of the wrench for selectively latching either of the said gripping jaws against slidable movement upon and relative to the said head of the wrench while allowing the other one of the said gripping jaws to be moved upon and relative to the said head of the said wrench against the action of the said coil tension spring, each of the said gripping jaws having a latching recess formed therein, the said manually adjustable latching means including a latch bar slidably mounted in the said head of the said wrench for slidable movement between the said gripping jaws, the said slidable latch bar having one end portion which is selectively latching engageable in the latching recess formed in one of the said gripping jaws, and the said slidable latch bar having another end portion which is latching engageable in the said latching recess formed in the other of the said gripping jaws.

2. A wrench as defined in claim 1 in which the said head of the said wrench has an arcuate slot formed therein and extending between and interconnecting the said sockets, and in which the said coil tension spring includes a central portion mounted in the said arcuate slot between the said sockets.
